(57) **CLAIM**

The ornamental design for a heat management unit for a hookah, as shown and described.

DESCRIPTION

FIG. 1 is a perspective view of an embodiment of a heat management unit for a hookah embodying the new design; FIG. 2 is a top plan view thereof; FIG. 3 is a bottom plan view thereof; FIG. 4 is a left side elevation view thereof; FIG. 5 is a right side elevation view thereof; FIG. 6 is a front side elevation view thereof; and, FIG. 7 is a back side elevation view thereof.

The shading lines only help to show the shape and do not depict any surface decoration.

The broken lines in the drawings depict portions of the heat management unit for a hookah that form no part of the claimed design.
